UNITED STATES PATENT OFFICE.

MARY K. MORSE, OF PHILADELPHIA, PENNSYLVANIA, EXECUTRIX OF HENRY G. MORSE, DECEASED, ASSIGNOR TO NEW YORK SHIP-BUILDING COMPANY, OF CAMDEN, NEW JERSEY, A CORPORATION OF NEW JERSEY.

APPARATUS FOR LAUNCHING SHIPS.

SPECIFICATION forming part of Letters Patent No. 759,734, dated May 10, 1904.

Application filed July 13, 1903 Serial No. 165,270. (No model.)

To all whom it may concern:

Be it known that HENRY G. MORSE, deceased, late a citizen of the United States, and a resident of the city and county of Philadelphia and State of Pennsylvania, did invent certain new and useful Improvements in Apparatus for Launching Ships, of which the following is a true and exact description, reference being had to the accompanying drawings, which form a part thereof.

The invention relates to apparatus for launching ships, and has for its object to provide a construction and mechanism which will cause the vessel to start on the slide down the ways with promptness and certainty.

In launching apparatus as heretofore generally constructed the weight of the ship has been relied upon to cause it to move down the way after the wedges have been driven, the ship set up upon the cradle, and the sawing-piece cut through; but it is well known that it is not infrequent for the vessel to "stick," and on such occurrences it has been usual to use hand-jacks in order to impart further movement to the ship; but the movement of these jacks is so slight and the difficulty of properly placing them and giving them the desirable coördination of movement so great that their use has been found to be a most unsatisfactory expedient.

The object of the invention is to provide as a part of the system of ways upon which the ship is supported and upon which it moves power mechanism of great power and ample range of movement and so placed as to operate in the most effective manner, and this is accomplished by a construction which will be best understood as described in connection with the drawings, in which the invention is illustrated in what is believed to be its best and most effective form.

In the drawings, Figure 1 is a side elevation showing the launching apparatus with a ship indicated as in position thereon. Fig. 2 is a plan view of the upper end of the launching apparatus shown on a larger scale. Fig.

3 is a plan view of one side of the launching apparatus, the upper end only being indicated and the scale being still larger than in Fig. 2. Fig. 4 is a side elevation of the mechanism as shown in Fig. 3. Fig. 5 is again a plan view of the part of the mechanism shown in Fig. 2, showing a desirable modification thereof, a system of conduits and valves for controlling the admission of fluid under pressure to the rams. Fig. 6 is a cross-sectional view taken approximately on the line 6 6 of Fig. 1, showing the parts on an enlarged scale. Fig. 7 is a longitudinal section through one of the rams, taken as on the line 7 7 of Fig. 8. Fig. 8 is a cross-section through the ram, taken on the line 8 8 of Fig. 7. Fig. 9 is a cross-section taken as on the broken line 9 9 of Fig. 4. Fig. 10 is a section on the line 10 10 of Fig. 9. Fig. 11 is a section on the line 11 11 of Fig. 4. Fig. 12 is a central sectional elevation of the accumulator used in connection with the apparatus. Fig. 13 is a side elevation of one of the controlling-valves used in the construction indicated in Fig. 2. Fig. 14 is a longitudinal section through the valve on the line 14 14 of Fig. 3, and Fig. 15 is a longitudinal sectional plan view of the controlling-valve as indicated in the construction shown in Fig. 5.

A and A' indicate the timber structure upon which the rear end of the ways are supported, A² indicating a system of piles or the like upon which the ways in the rear of this timber structure are supported, a' indicating the platform upon which the permanent ways (indicated at B B) are supported, B' B' indicating timbers projecting above the outer edges of the permanent ways and serving as the abutments to hold the sliding ways in position. These sliding ways are in turn indicated at C C, their upper ends (indicated at C²) being securely bolted, as is shown in Figs. 3 and 4, to the permanent ways and the supporting-timber.

e (indicated in Figs. 3 and 4 by dotted lines) is the place where the saw cut is made which separates the sliding way from the permanent way, and just in the front of this place for the

saw cut is built up a strong upwardly-extending abutment, (shown at C'), securely fastened to the sliding way C.

D is a beam or brace preferably made of structural iron or steel, as shown, and firmly secured to a permanent part of the rear end of the way structure, preferably directly on top of the portion C² of the sliding ways which is permanently secured to the substructure, 10 as is shown, for instance, in Figs. 3, 4, 9 and 10.

D' D' indicate abutment-plates for the rear ends of the ram-cylinders, which are firmly secured to the beams D, as shown, and D² D² indicate pins secured to beam D, as shown in Fig. 9, and extending through eyes in the strips, (indicated at E E,) which extend rearwardly and are bolted to the permanent supporting structure at their rear ends, as indicated at E'.

20 F F are ram-cylinders supported, as shown, on the top of the stationary portion C² of the sliding ways, and their ends abut against the abutments D' of the beams D.

F' (see Fig. 7) is a stuffing-box gland at the open end of the cylinder, F² the head closing the opposite end of the cylinder, F³ and F⁴ ports entering the opposite ends of the cylinder, f³ f⁴ cocks connected with other ports entering the opposite ends of the cylinder, F⁵ indicating the space left between the plunger G and the sides of the cylinder back of the front end, where the piston fits the cylinder, as shown.

G' indicates the piston at the rear end of the plunger G, and G² the plunger-head.

H is a conduit by which fluid enters a high-pressure pump, (indicated at I, Fig. 1,) H' indicating the high-pressure conduit leading from the pump and having a branch H², which communicates with an accumulator, (indicated at I', Figs. 1 and 12.) This accumulator may be of any convenient construction. As shown, it consists of an upwardly-extending cylinder I², with which the conduit H² communicates at 45 bottom and over which fits and slides the cylinder I³, supporting at its bottom the weighted receptacle indicated at I⁴. The high-pressure conduit H' communicates with the ram-cylinders, passing in the construction shown in Figs. 5 and 15, which is the one which it is 50 preferred to employ, the high-pressure conduit H' communicates through a T-head (indicated at H³) with the valve indicated at J and also with the side conduit indicated at H⁵. From the valve J a continuation of the conduit indicated at H⁴ communicates, through branches H⁶ and h⁶, with the rear ends of the cylinders F F, as shown, and these branches also communicate, through a pipe H⁹, in which is situated the stop-valve K, with an exhaust-conduit, (indicated at h⁹.) The conduit H⁵ in

turn communicates, through branches H⁷ and h⁷, with the rear ends of the cylinders F F, as shown, and these branches also communicate, through branch conduits indicated at H⁸ and h⁸, each having a stop-valve, as indicated at 70 M and m, with the exhaust-conduit h⁹. The valve J, (see Fig. 15,) which is of the globe type, is provided with a valve-seat J', upon which is seated a valve having a cylindrical extension, as indicated at J², the cylindrical extension fitting in an open-ended cylinder, (indicated at J³.) The valve J² has a valve-seated port (indicated at J⁴) extending through it, which is closed at proper times by a valve J⁵, formed on a head having a certain play to 80 and from the valve-seat and connected in turn with a valve-spindle J⁶, which is operated by a lever J⁷, pivoted to a link J, the lever having secured near its handle end a rod J⁹, which (see Fig. 5) is connected to a rod j⁹, having 85 on it a stop J¹⁰, by an elastic coupling—that is to say, the rod J⁹ extends into a hollow sleeve N', secured to the rod j⁹, and is connected therewith through a spring N³, which is fast at one end to a pin N², secured to the sleeve 90 N', and to the other end at a collar N, secured on the rod J⁹. In the construction shown in Fig. 5 the ram-heads G² have extending up from them pins g² g², which pass through slots in the ends of a cross-extending bar, (indicated 95 at G³.) said bar having at a convenient point a bearing and stop, (indicated at G⁴.) through which extends the rod j⁹.

In the modification illustrated in Figs. 12, 13, and 14 the branches H' H' of the high-pressure conduit lead to the valve-casings indicated at O and into chambers O' of said casings, which communicate, through appropriate ports, with cylindrical chambers, (indicated at O².) said chambers communicating at 105 top and bottom with enlarged chambers O³ and o³. O⁴ and o⁴ indicate the separable ends of the valve-chamber, which are formed with cylindrical bearings, (indicated at O⁵ and o⁵.) with lateral ports, (indicated at O⁶ and o⁶.) 110 said ports leading into chambers connected with the ports O' o', which in turn communicate, through a common port O⁸, with the exhaust-conduit H¹¹. The chambers O³ o³ in the valve-casing communicate, through ports O⁹ 115 and o⁹, (see Fig. 13,) with the conduits H⁷ H⁶, leading, respectively, to the rear and front ends of the cylinders F, as shown in Fig. 2. P, Figs. 13 and 14, is a valve-stem, to which is secured the piston-valve (indicated at P') 120 having the long ends, to which in turn are secured the sleeved cylinders, (indicated at P² and p².) having ports P³ p³ formed through their sides, as shown. The valve and its connections are operated through the hand-lever 125 P', fulcrumed on the link P⁵.

Q, Figs. 1 and 6, indicates the cradle, supported on the sliding ways C C and adapted to support the vessel on said ways when the wedges (indicated at Q²) are driven in. The 130

cradle-sections are connected, as shown, by tie-rods Q', and in these features of construction the apparatus does not differ from those commonly in use.

- 5 R indicates the ship supported on the ways. It will be seen that the rams G are normally in retracted position, their heads resting in contact with the abutments C', built up on the sliding ways C. When it is desired to launch 10 the vessel, the wedges are driven and the ship thus supported on the sliding ways through the cradle, and the sliding ways are then cut through at the points indicated at c c, Figs. 3 and 4. The high-pressure conduit H' is under the full pressure provided for by the accumulator, and immediately on the severance of the sliding ways the operator, taking first 15 the construction shown in Fig. 5, pushes the hand-lever J' outward, so as to lift the valve J' from its seat and permit the high-pressure fluid to pass to the conduits H' H', the stop-valve K being closed by preference and the valves M and m being closed and the valve L opened. The high-pressure fluid is then admitted 20 to the ram-cylinders F F through the ports F' F', and acting on the piston G' of the ram-plungers the pressure forces the rams outward, and the heads G' of the rams abutting against the abutments C' of the sliding ways 25 30 said sliding ways and the vessel supported thereon are moved forward with great power through a very considerable distance and with an accelerating speed which under any conditions to be anticipated will impart sufficient momentum to the mass to insure the launching 35 of the vessel.

In the arrangement of valves which has been stated to be preferable the fluid contained in the space F' of the ram-cylinder will be forced 40 out through the conduits H' h' and the conduit H' into the pressure-conduit H'; but obviously the same results practically could be secured by closing the valve L and opening the valves M and m, in which case the fluid in 45 the chambers l' will be forced out through the exhaust-conduit h'.

In order to avoid forcing piston G' of the plunger into actual contact with the contracted front end of the cylinder F, the construction 50 shown in Fig. 5 is provided, consisting of the cross-bars G' and the rods attached to the hand-lever J', as described, said bar G' moving forward with the rams until its guiding-abutment G' comes in contact with the 55 stop J', after which the bar j' moves forward with the cross-bar g', drawing with constantly augmented pressure through the spring M' upon the rod J', which through its connection with the lever J' acts to successively close the valves J' and J', cutting off 60 the pressure-supply to the cylinders and arresting the motion of the rams. When it is desired to move the rams back to their normal rearmost position, the stop-valves K and 65 L are opened and the pressure in the high-

pressure main admitted to the conduit H' H' h' to the front ends of the ram-cylinders, whereupon the rams will move backward, the fluid in the rear ends of the cylinders escaping through the exhaust-conduit h'. The cocks indicated at f' and f' permit another way of exhausting fluid from either end of the cylinders. 70

In the construction indicated in Figs. 1, 2, 13, and 14 each cylinder F is provided with an independent controlling-valve requiring a 75 separate operator, the valve P' being normally in the position shown in Fig. 14. When it is desired to admit pressure fluid from the conduit H' to actuate the plunger-cylinder, the operator moves the lever P' backward, the 80 fluid then passing from the chamber O', through the valve-cylinder o', into the chamber o', and thence through the conduit H' to the rear end of the cylinder F. At the same time the front end of the cylinder F is placed 85 in communication with the exhaust-pipe H', the upward movement of the valve carrying the sleeve P' upward until its lateral ports p' communicate with the chamber in the head O', whereupon the fluid in the chamber F' 90 will pass out through the conduit H' into the chamber O', thence through the sleeve P' and its port P' into the chamber of the head O', and thence through the port O' and ports O' and O' to the exhaust H'. When it is desired 95 in this construction of valve to return the plungers to normal retracted position, the lever P' is moved downward, reversing the position of the valve and its connections, whereupon the high-pressure fluid is admitted 100 to the front end of the cylinder F and the fluid in the rear end of the cylinder permitted to exhaust.

Having now described the invention, what is claimed as new, and desired to be secured by Letters Patent, is—

1. An apparatus for launching ships having in combination fixed and sliding ways, a ram or rams arranged to act upon the sliding ways, a high-pressure main carrying constant pressure connected with the rams and a valve or valves controlling the admission of the high-pressure fluid to the rams. 110

2. An apparatus for launching ships having in combination fixed and sliding ways, the sliding way being firmly secured to the fixed way at its rear end and having a stop or ram abutment, secured to it forward of the point where the saw-cut is to be made, a ram or rams firmly secured to the fixed ways and having a head or heads abutting against the stops on the sliding ways, a high-pressure main carrying constant pressure connected to the ram or rams and a valve or valves controlling the connection between the main and the rams. 120

3. An apparatus for launching ships having in combination fixed and sliding ways, the sliding way being firmly secured to the fixed way at its rear end and having a stop or ram abutment, secured to it forward of the point where 130

the saw-cut is to be made, a ram or rams firmly secured on the rear or fixed end of the sliding ways and also to the fixed ways and having a head or heads abutting against the stops on the sliding ways, a high-pressure main carrying constant pressure connected to the ram or rams and a valve or valves controlling the connection between the main and the rams.

4. An apparatus for launching ships having in combination fixed and sliding ways, the sliding way being firmly secured to the fixed way at its rear end and having a stop or ram abutment, secured to it forward of the point where the saw-cut is to be made, a beam or beams adapted to serve as a ram-abutment secured on the rear fixed ends of the sliding ways and held in place by straps extending from the beam obliquely forward and firmly secured at their front ends to the fixed ways, rams having cylinders abutted against the beam or beams and plungers abutted against the stops on the sliding ways, a high-pressure main carrying constant pressure connected to the ram-cylinders and a valve or valves controlling the connection from said main to the ram-cylinders.

5. An apparatus for launching ships having in combination fixed and sliding ways, the sliding way being firmly secured to the fixed way at its rear end and having a stop, or ram abut-

ment, secured to it forward of the point where the saw-cut is to be made, a beam or beams adapted to serve as a ram-abutment secured on the rear fixed ends of the sliding ways and held in place by pin-connected straps extending from the beam obliquely forward and firmly secured at their front ends to the fixed ways, rams having cylinders abutted against the beam or beams and plungers abutted against the stops on the sliding ways, a high-pressure main carrying constant pressure connected to the ram-cylinders and a valve or valves controlling the connection between the main and the rams.

6. An apparatus for launching ships having in combination fixed and sliding ways, a ram or rams arranged to act upon the sliding ways, a high-pressure main carrying constant pressure connected with the rams, a valve or valves controlling the admission of the high-pressure fluid to the rams, and mains controlled by the movement of the rams for closing the valves at the end of the determined ram-stroke.

MARY K. MORSE,
Executrix of the estate of Henry G. Morse, deceased.
